UNITED STATES PATENT OFFICE.

JOHN P. KNOBELOCH, OF PHILADELPHIA, PENNSYLVANIA.

AWNING-VENTILATOR.

SPECIFICATION forming part of Letters Patent No. 380,207, dated March 27, 1888.

Application filed August 17, 1887. Serial No. 247,165. (No model.)

To all whom it may concern:

Be it known that I, JOHN P. KNOBELOCH, a citizen of the United States, and a resident of Philadelphia, Pennsylvania, have invented 5 certain Improvements in Awning-Ventilators, &c., of which the following is a specification.

The object of my invention is to provide a simple and effective device for application to window or veranda awnings, tents, &c., for 10 the purpose of ventilating the room or apartment shaded or inclosed thereby, and this object I attain in the manner hereinafter set forth, reference being had to the accompanying drawings, in which—

15 Figure 1 is a perspective view of a window-awning provided with ventilators constructed in accordance with my invention, the awning being shown in its extended position. Fig. 2 is a similar view showing the awning folded 20 up. Fig. 3 is a perspective view of one of the ventilators and its confining-frame. Fig. 4 is a sectional view showing the position assumed by the ventilator when applied to the awning, and Fig. 5 is a sectional perspective view of 25 one of the side ventilators.

Ordinary window-awnings which extend up to the top of the window-frame are objectionable, because they interfere with the proper ventilation of the room or apartment to the 30 windows of which they are applied, and veranda awnings, tents, &c., are subject to the same objection. In order to overcome this objection, I provide the upper portion of the awning A with one or more ventilators, B, so 35 constructed as to permit the free ingress or egress of air, and yet intercept the rays of the sun or the passage of rain, said ventilator or ventilators being located in that portion of the awning which is not covered by the folds 40 of the awning when the latter is folded, as shown in Fig. 2, so that the ventilator is operative whether the awning is extended or folded up.

The ventilator which I prefer to use consists of a plate, a, having a series of inclined 45 projecting hoods, b, overlapping each other to such an extent that when the ventilator occupies the position shown in Fig. 4, as it does when the awning is extended, rays of sun- 50 light, even though actually horizontal, cannot

enter the room through the same, nor can rain beat in through the ventilator, the latter, however, providing for the free ingress and egress of air at all times.

The plate a is secured to the awning by 55 means of a confining-frame, d, having spurs f, which are passed through the material of which the awning is composed, and are bent down on the under side of the same, although it will be evident that the use of this frame is not 60 absolutely necessary, as the spurs may be formed directly on the plate a, if desired, or the latter may be secured to the awning by eyelets or other equivalent means.

In the side wings, D, of the awning are 65 ventilators F, each consisting of a frame, g, carrying a series of hinged flaps, h, as shown in Fig. 5, each flap having at the ends projecting journals adapted to bearings in ears i, preferably struck up from the metal of the frame, as 70 shown. The flaps h are thus free to swing in either direction and permit the ready ingress and egress of air through the side wings of the awning when the latter is extended.

The frame g is secured by a frame, d, similar to that which secures the plate a of the 75 ventilator B.

In the present instance I have shown two ventilators at the upper portion of the awning; but it will be evident that one ventilator 80 of proper size or more than two ventilators may be used, if desired.

I claim as my invention—

1. The combination of a folding awning with a ventilator applied to that portion of the fabric of the awning which is above the folds when the awning is raised, all substantially as 85 specified.

2. The combination of a folding awning with ventilators applied to the side wings of the 90 same and to that portion of the body of the awning which is above the folds when the awning is raised, all substantially as specified.

3. The combination of an awning or like structure with a ventilator applied to the body 95 of the same so as to assume an inclined position when the awning is down, said ventilator consisting of a frame having fixed hoods projecting at an angle and overlapping each other, all substantially as specified. 100

4. The combination of an awning or like structure with a ventilator consisting of a frame, and a series of flaps hung thereto and located one above another, the pendent portion 5 of each flap being free from contact with the frame or adjacent flap, whereby it is free to swing in both directions, all substantially as specified.

In testimony whereof I have signed my name to this specification in the presence of two sub-
scribing witnesses.

JOHN P. KNOBELOCH.
